Filed Aug. 13, 1962, Ser. No. 71,269

Term of patent 14 years

(Cl. D87—5)

FIG. 1

FIG. 2

FIG. 3

FIG. 4

FIG. 5

FIG. 1 is a perspective view of the front, right side and top side of a carrying case for bar equipment or the like embodying our new design;

FIG. 2 is a front perspective view thereof with the carrying case in an open position;

FIG. 3 is a rear elevational view thereof;

FIG. 4 is an elevational view of the other side thereof; and

FIG. 5 is a bottom plan view thereof.

The characteristic feature of our design resides in the provision on the front wall of a carrying case for bar equipment or the like having the configuration shown of a recessed rectangular area which extends downward from a point near the top of the case to and around the bottom edge terminating on the bottom of the case at the point where the two sections of the case are joined together, all as shown.

We claim:

The ornamental design for a carrying case for bar equipment or the like, as shown and described.
